UNITED STATES PATENT OFFICE.

CHARLES A. DIECKMAN, OF WARRENTON, MISSOURI.

ANVIL-BLOCK.

1,093,320.

Specification of Letters Patent.

Patented Apr. 14, 1914.

Application filed October 8, 1913. Serial No. 794,004.

To all whom it may concern:

Be it known that I, CHARLES A. DIECKMAN, a citizen of the United States, residing at Warrenton, in the county of Warren and State of Missouri, have invented certain new and useful Improvements in Anvil-Blocks; and I do hereby declare the following to be a full, clear, and exact description of the invention, such as will enable others skilled in the art to which it appertains to make and use the same.

This invention relates to anvils specially adapted for use in connection with plows; and it consists of an anvil block or anvil formed as hereinafter fully described and claimed.

In the drawings, Figure 1 is a plan view of an anvil block constructed according to this invention. Fig. 2 is an end view of the block. Fig. 3 is a side view. Fig. 4 is also a side view, but looking in the opposite direction from Fig. 3.

The block 2 forms the top portion of an anvil, and it may be formed or forged solid with the base of the anvil, or it may be formed separate from the anvil as ordinarily constructed and arranged to rest on it. When formed separate from the anvil, the block 2 has suitable flanges 3, or other approved means, for positioning it on the anvil.

The block 2 has a flat surface 4 at one end for the landside of the plow, and it has a raised portion 5 at its middle part. The raised portion 5 has a vertical end 6 adjacent to the surface 4, and this end 6 is arranged diagonally of the block so that a point 7 is formed at one side edge of the block.

The surface of the raised portion 5 is inclined to the horizontal, the longer side 8 of the raised portion being much lower than its

opposite and shorter side. The side edge 8 forms an abutment for the plow share and against which its edge is sharpened. The 45 pointed portion 7 forms an abutment for use in welding the plow point to the plow share, and it enables the point to be welded on without kinking the share.

The lower part 9 of the raised portion 5 50 adjacent to the side edge 8 is slightly concave, as shown in Fig. 4, so that the pointed portion forms a good abutment. The other end 10 of the raised portion 5 from the point is arranged at substantially a right angle to 55 the sides of the block and is rounded over. A slot 12 is formed crosswise of the block parallel to the end 10 and at a comparatively short distance from it. This slot is used in leveling or straightening the landside, and its bottom is inclined upwardly 60 from the thicker to the thinner part of the raised portion 5. The slot 12 is also inclined a little from the vertical.

What I claim is:

A plow anvil, comprising a block having a flat surface at one end portion, and having a raised portion adjacent thereto, said raised portion having one end arranged diagonally of the block and forming a point at one side 70 of the block, the pointed side of the raised portion being longer than its opposite side and the surface of the block being inclined from its shorter to its longer side, and the opposite end portion of the raised part being 75 rounded and provided with a slot extending crosswise of the block.

In testimony whereof I have affixed my signature in the presence of two witnesses.

CHARLES A. DIECKMAN.

Witnesses:

J. E. PETERSON,
J. M. BORBEE.
